UNITED STATES PATENT OFFICE.

RICHARD E. STANLEY, OF PITTSBURGH, PENNSYLVANIA, ASSIGNOR OF ONE-THIRD TO JOHN N. BARNETT AND ONE-THIRD TO CHARLES BITZER, JR., BOTH OF PITTSBURGH, PENNSYLVANIA.

BOWLING-PIN.

1,144,070.

Specification of Letters Patent. Patented June 22, 1915.

Application filed October 17, 1914. Serial No. 867,176.

To all whom it may concern:

Be it known that I, RICHARD E. STANLEY, a citizen of the United States, residing at Pittsburgh, in the county of Allegheny and 5 State of Pennsylvania, have invented certain new and useful Improvements in Bowling-Pins, of which the following is a specification, reference being had to the accompanying drawings.

- 10 This invention relates to an improved bowling pin, and has for its primary object to provide a hollow metal pin and improved means for balancing the pin so that it will maintain an upright position.
- 15 The invention has for an additional object to provide a bowling pin of the above type embodying means whereby the same is prevented from shifting or jumping from its set position upon the spot.
- 20 It is a further object of my invention to produce a bowling pin having the above noted advantageous characteristics which may be produced at small manufacturing cost, and is very durable and serviceable in 25 actual use.

With the above and other objects in view, my invention consists in the novel features of construction, combination, and arrangement of parts to be hereinafter more fully 30 described, claimed, and illustrated in the accompanying drawing, in which,

Figure 1 is a side elevation of a bowling pin embodying the present invention; and Fig. 2 is a vertical section of the same.

35 Referring in detail to the drawing, I have illustrated a pin of the character commonly employed in a game of duckpins. It is, however, to be borne in mind that the structural features hereinafter referred to, are 40 applicable as well as to the larger pins which are used in playing the game of tenpins.

The pin 5 includes a hollow body 6 of general elliptical form, one end of which is truncated to provide a flat base indicated 45 at 7. The body of the pin at its other or upper end, merges into a reduced neck portion 8, said neck portion terminating in the slightly enlarged rounded head 9 of the pin. This pin is formed of a metallic mixture, in which aluminum predominates. The pin is produced by the process of casting, the molten metal being poured into a suitable mold. The body 6 of the smaller or duckpin is provided in its medial portion 50

with an annular peripheral groove or channel indicated at 10 in which a band of rubber or other resilient material 11 is placed. The outer face of this strip or band extends slightly beyond the periphery of the pin body. It is, however, apparent that this provision 60 for the reception of a rubber band may be eliminated in the construction of the duckpin as well as the tenpin.

In the base 7 of the pin, a central hole or opening 12 is formed, and the head 9 of 65 the pin is provided with an integral anchoring lug 13 which extends centrally and longitudinally inwardly from the wall of the head. This anchoring lug may be either rectangular or cylindrical in form and is 70 gradually reduced in width or tapers from its end to its point of juncture with the wall of the head 9. After the hollow metal pin has been removed from the mold, a predetermined quantity of molten lead is poured 75 in the same through the opening 12 and around the anchoring lug 13, as indicated at 14. After this lead solidifies, it will be retained in place within the head of the pin by the anchoring lug as will be readily understood.

80 By constructing the pin in the manner above explained, it will be manifest that all of the pins will be of precisely the same weight. It is quite difficult, if not impossible, to attain this purpose in the manufacture of the ordinary wooden bowling pin. Such pins, after a short period of use, will be found to greatly vary in weight. It is highly desirable, in order that the pins shall 85 offer uniform resistance to impact, that they at all times be of the same weight. As my improved pin is entirely constructed of metal which is of requisite thickness to withstand the impact of the bowling balls, wear 90 of the pins is comparatively insignificant. It is also seen that by the provision of the opening 12 in the base of the pin, molten lead may be poured into the head of the pin to compensate for such wear as does occur. 95 In this manner, all of the pins may be maintained at a uniform weight. It will further be apparent that by providing the pin with the flat base having the opening 12 therein, there is a comparatively restricted surface 100 which has frictional contact with the floor or alley so that the movement of the pin will not be retarded when struck by the ball, but

said pin will fall immediately over to a horizontal position, owing to the weight in the head thereof.

From the foregoing description, the construction and several advantages of my improved bowling pin will be apparent. While I have produced a pin which is manifestly of greater serviceability than the ordinary wooden pin, it will be appreciated that the 10 manufacturing cost thereof is not increased to an appreciable extent. The neck, head and body portions of the pin are, of course, of the same standard required dimensions. The thickness of the wall of the pin is determined in accordance with the required 15 weight of the particular type of pin to be produced.

While I have referred to the preferred manner of retaining the balancing weight 20 within the head of the pin, it will be understood that the present invention also contemplates the provision of other equivalent means for this purpose. I do not, therefore, desire to be limited to the precise structural 25 features above described, but reserve the privilege of resorting to all such legitimate changes as may be fairly embodied within the spirit and scope of the invention as claimed.

30 Having thus fully described my invention, what I desire to claim and secure by Letters Patent, is:—

1. A hollow metal bowling pin, a balancing weight insertible into the head of the 35 pin, and means projecting into the pin head longitudinally thereof to retain said weight in position.

2. A hollow metal bowling pin, an anchoring lug projecting into the head of the 40 pin from the wall thereof, and a weight element immovably held in the head of the pin by said lug.

3. A hollow metal bowling pin, an inwardly projecting tapering lug formed 45 upon the head of said pin, and a weight element surrounding said lug and immovably held thereby in the head of the pin.

4. A hollow metal bowling pin having an integral tapering lug projecting longitudinally from the wall of the pin and through

the head thereof, and a weight element surrounding said lug and immovably held by the lug within the head of the pin.

5. A hollow metal bowling pin having an anchoring lug integrally formed with the 55 wall thereof and projecting into the head of the pin, said pin being provided with an opening in its base through which balancing means may be inserted and associated with said lug to be retained thereby within 60 the head of the pin.

6. A hollow metal bowling pin having a longitudinally tapering anchoring lug integrally formed upon its wall and extending longitudinally into the head of the pin, said 65 pin being provided with an opening in its base through which molten lead is adapted to be poured into the head of the pin around said anchoring lug.

7. A bowling pin having a hollow non-flexible body provided with an unobstructed opening in its base, and weighting means insertible through said opening into the head of the pin, the pin head being provided with means to receive said weighting means 75 and retain the same in position with its center of gravity in line with the longitudinal axis of the pin.

8. A hollow bowling pin provided with means whereby fluid metal may be poured 80 into the head thereof to solidify and constitute a balancing weight, and means on the head of the pin to retain said weight in position with its center of gravity in line with the longitudinal axis of the pin.

85 9. A hollow metal bowling pin provided with an opening in its wall through which fluid metal may be poured into the head of the pin to solidify and constitute a balancing weight, and means on the head of the pin to permanently retain the weight in position with its center of gravity in line with the longitudinal axis of the pin.

In testimony whereof I hereunto affix my signature in the presence of two witnesses. 95

RICHARD E. STANLEY.
